CLAIM

The ornamental design for an acoustic light fixture as shown and described.

DESCRIPTION

FIG. 1 is a perspective view of the acoustic light fixture;

FIG. 2 is a left side view thereof;

FIG. 3 is a right side view thereof;

FIG. 4 is a rear side view thereof;

FIG. 5 is a front side view thereof;

FIG. 6 is a top view thereof; and,

FIG. 7 is a bottom view thereof.

The broken lines showing the acoustic light fixture is for the purpose of illustrating the acoustic light fixture and form no part of the claimed design.

1 Claim, 10 Drawing Sheets
